UNITED STATES PATENT OFFICE

JOSEPH H. POPE, OF HAMILTON, MASSACHUSETTS, ASSIGNEE TO UNITED SHOE MACHINERY CORPORATION, OF PATERSON, NEW JERSEY, A CORPORATION OF NEW JERSEY

MACHINE FOR OPERATING UPON HEELS

Application filed March 8, 1926. Serial No. 93,269.

This invention relates to machines for operating upon heels, being of particular utility in connection with apparatus known as pricking machines, and which are employed 5 for piercing heels in preparation for driving nails therein.

Heretofore, pricking machines, of which an example is disclosed in United States Patent No. 1,234,384, issued on my application 10 July 24, 1917, have been fed by hand, the heels to be pricked being laid one by one by the operator in the path of an oscillatory lever which acts to carry them successively between a templet, through openings in 15 which operate awls, and a reciprocatory follower, which serves to press each heel against the templet to resist the pricking pressure of said awls. Objects of the invention are to provide for the successive delivery of heels 20 mechanically to the operating mechanism from a source of supply at which a plurality of said heels may be maintained, thus enabling the operator to employ a portion of his time for other than feeding operations 25 while the pricking of the heels is going on; and to locate these heels with precision, for the operation upon them, regardless of variations in their weight and contour.

A feature of the invention leading to the 30 attainment of these objects involves the delivery of heels directly from a container to a pricking mechanism, with the contained stack supported by a heel in pricking position, this delivery being preferably under 35 the influence of gravity. By this arrangement, there is not alone a continuous feed of heels assured, but also the number of elements employed for this purpose and the opportunities for displacement during the 40 travel of the heels are minimized. In the particular embodiment of the invention herein illustrated, the pricking is accomplished by awls co-operating with a templet, and to this templet heels are delivered from 45 a magazine, which is shown as rising above a space formed between the templet and a pressure member or follower, which holds the heel against the force of the awls. The heel-delivery may be under the control of a 50 retaining member associated with the maga-

zine, while a support receives the delivered heels for the pricking operation, and is moved to discharge them thereafter. To insure correctness of feed, the pricking mechanism, retaining member and support are operated in synchronism, and the time-relation between these elements may be varied.

A further feature provides, in a simple manner, for the proper delivery from the container to the pricking or other operating mechanism and the action of said mechanism upon the work, by supporting one of the container-walls upon another in such a manner as to permit the supported wall to be adjusted 55 in directions at different angles to the operating mechanism. The container-walls may be in sections, two of these sections being movable toward and from each other, as laterally of the path of the operating mechanism, 60 while two other sections are movable, upon those just mentioned. In the present instance, this alteration in the position of the last-mentioned sections is both toward and 65 from the companion sections and toward and from the operating mechanism. Such changes in the container adapt it to receive heels of different width and height, locate them symmetrically with respect to the awls by which they are to be pricked, and free, in 70 the most effective manner, from certain of the container-walls, heels which are of different dimensions considered from the breast rearwardly. The preferred mounting for the 75 wall-sections includes a device carried by one of said sections and arranged to support and vary the position of another, while the position of the last-mentioned section may be further adjusted upon said device. This furnishes a convenient and compact means for 80 changing the dimensions of the container. 85

When there is applied to a machine, such as that of the patent previously mentioned, a magazine-feed, the movable fork by which the heels to be operated upon are clamped over the face of the templet becomes, to a considerable extent, unnecessary, because of the weight of the column of heels in the magazine, and it also interferes with the preferred arrangement of said magazine. However, 90 95 100

with certain types of heels, as the wedge-form, in which the heel-seat end may lie at a considerable angle to the tread-surface, the pressure of the follower, through its component parallel to the face of the templet, tends to force the clamped heel out of prickling position. A feature of the invention overcomes this tendency, and holds the heels in correct relation by means of a positioning member co-operating with the templet and fixed against movement in the operation of the machine. This positioning means, which preferably consists of a gage-plate supported upon the templet out of the path of heels falling from the magazine, may resist displacement of the heel in a plurality of directions. Thus the heel may not only be held against upward movement when the follower pressure is applied, but may also be centered laterally. I prefer to make the normal relation between the templet and positioning member adjustable, as by varying the location of the member upon said templet independently of any movement which the templet itself may have.

It is desired to have between the templet and pressure member or follower a sufficient space, without adjusting said follower, to receive heels differing somewhat from one another in height. It is also advantageous, especially in machines of the type herein illustrated, from which the clamping fork is omitted, to have this space such that a heel fed from the magazine may not become so displaced from prickling position that the awls will fail to enter it in the proper direction. An additional feature of my invention allows the lowest heels of a range of heights to so contact with the follower that their position will be maintained, while the higher heels will not be subjected to undue pressure in the clamping movement of the follower. For this purpose, I utilize yieldable connections between the follower or pressure member and its actuating means. The relation between the elements is preferably such that, for the highest heels to be operated upon with one follower-adjustment, the space between the follower and templet will be just wide enough to admit them, the connections yielding until the follower reaches the point of application of full pressure. For lower heels, the excess of space between them and the follower is too little to allow displacement, and the springs, while less compressed, exert sufficient retaining force. In the present instance, the follower is mounted opposite the templet upon a reciprocatory slide, and between the follower and slide springs are interposed.

In the accompanying drawings is shown one of several embodiments which my invention may assume. Here,

Fig. 1 is a vertical transverse section 65 through my improved machine;

Fig. 2 is a broken side elevation of the elements more closely co-operating with the work;

Fig. 3 is a top plan view of the heel-supporting mechanism and actuating means 70 therefor; and

Fig. 4 is a perspective view of the magazine and associated elements of the prickling mechanism.

Mounted upon a portion 10 rising from a base 12 is a templet 14, in which are horizontal openings 15 arranged in accordance with the design which is to be prickled. This templet serves as an abutment, against which the heel is pressed for the piercing or prickling operations which are to be performed. The templet slides vertically in ways 16, and is supported and adjusted to locate the openings in the proper relation to the work by a screw 18 fixed in the templet and threaded into a vertical spindle 20 rotatable in a yoke 22 extending between the sides of the frame-portion 10. Upon the screw is a nut 24, by which, through its contact with the end of the spindle, said spindle may be held against turning. When this nut is loosened and the spindle rotated, as by engagement with spanner-openings 26 at its upper extremity, the templet is raised or lowered in its ways, and may then be fixed at the chosen height by again tightening the nut. Operating in the templet-openings are awls 28 projecting horizontally from a block 30 mounted upon a carrier-slide 32, this slide being movable horizontally in ways upon the frame. At the opposite side of the templet from the slide 32 is a carrier-slide 34 movable similarly to said slide 32, and carrying upon it, in a horizontal position, a spindle 36, which, at its inner end, has fixed a pressure-head 38 supporting a pressure-block or follower 40. The contour of the pressure-face of this block corresponds generally to that of the heel-seat-end of the heels to be operated upon, so that they may be most effectively engaged to be forced against the templet. The spindle is threaded between spaced portions of the carrier 34, and may be advanced toward the templet or retracted by a nut 42. Projecting through openings in the pressure-head toward the templet are studs 44, which may be three in number. These studs carry at their inner extremities the follower 40, and between the inner side of this follower and the head, surrounding the studs, are interposed helical springs 46, which yieldably urge the follower toward the templet. The effect of this yield upon the operation of the machine will be later developed. Movable 105 in the frame, beneath the carrier-slides 32 and 34, is a main actuating-slide 48 reciprocated by a connecting-rod 50 from a crank-shaft 51 rotated from a power-shaft (not shown) through gearing 52. The action of 110

this slide 48 upon the carrier-slides may be precisely as in Patent No. 1,234,384. It first carries the follower toward the templet to clamp a heel against the openings 15. Then the awls are advanced through the openings for the pricking operation, and withdrawn; after which the follower is retracted to free the pricked heel. As in the specified patent, the awl-block and the follower may be varied 5 in position vertically to correspond to the templet-adjustment, and horizontally to determine their normal locations, and therefore the points to which they respectively travel to pierce the heels and to apply the 10 necessary resisting pressure for heels of different heights.

Rising from the frame-portion 10, above the templet, so it may deliver directly to the space between the inner face of said templet 20 and the follower, is a vertical magazine M arranged to contain a series of heels H to be operated upon. The heels are preferably situated in the magazine breasts down, the tread-end being toward the templet, and the 25 heel-seat-end toward the follower. This magazine, as illustrated, has wall-sections 54, 54 and 56, 56, so mounted that the lowest heel of the contained series may be delivered accurately as to its transverse relation to the 30 templet-openings, and at the same time the sections of each pair may be so spaced that they properly engage the particular width of heel which is to be fed. In addition, each of the sections 56 is adjustable horizontally 35 toward and from one of the sections 54 in the direction of travel of the awls to arrange the magazine to contain heels of different heights, and vertically toward and from the path of the awls so that the heel-seat-end of the 40 terminal heel, or that to be operated upon, is just exposed to receive the clamping pressure of the follower. The sections 54 are L-shaped in horizontal section, and are fixed at their lower extremities to plates 58 secured 45 to vertical faces of the frame-portion 10 at opposite sides of the templet. Screws 60 passing through horizontal slots in the plates and being threaded into the frame-portion serve to fix the walls 54 in the desired 50 relation to the templet-openings. Since the sections 54 may be independently adjusted both with respect to each other and to the templet, this provides both for the co-operation of the magazine with heels of different 55 widths, and also for their symmetrical location opposite the templet-openings. As a convenient manner of effecting these adjustments, each plate 58 has threaded into it a screw 62 turning in a bracket 64 at the outer 60 side of the frame-portion 10. By rotating either of the screws, a plate, and therefore the magazine-section 54 which it bears, is moved inwardly or outwardly. I prefer to mount each wall-section 56 upon one of the 65 wall-sections 54, so that one entire half of

the magazine receives the adjustment imparted by a screw 62. For this purpose, there projects horizontally from the sections 54, at their upper and lower portions, supporting and adjusting devices, each consisting of a stud 66 having arranged to slide upon it a sleeve 68 forced by a helical spring 70 against a nut 72 upon the threaded end of the stud. Extending inwardly from the sleeves are projections 74 passing through vertical slots in the wall-sections 56, and threaded at their ends to receive nuts 76. By turning the nuts 72 in one direction, the sections 56 may be forced in against the springs, so that the magazine is adapted to receive heels of less height. Upon reversing the direction of 70 rotation of the nuts, the springs act to force out the wall-sections 56, so that the magazine may contain heels of greater height. By changing the positions of the sections 56 upon the adjusting devices, by loosening the nuts 76 and either lowering or raising the sections along the projections 74, the relation between the lower ends of these walls and the upper portion of the follower 40 may be varied. 75 This permits the creation of a space just sufficient to free the heel for engagement by the follower, while retaining the heel as long as is possible against falling forward. The tops of both pairs of wall-sections may be curved outwardly, as is indicated at 78, to facilitate the introduction of the heels by the operator into the throat thus formed.

To successively present the heels from the magazine to the pricking mechanism, supporting means is situated below the magazine and templet and just at the front of the latter. This may consist of horizontal sliding plates 80, 82 movable upon the frame in ways 84. The inner or adjacent edges of these plates normally lie at substantially equal distances on opposite sides of the center of the templet, being so spaced that the breast-corners of the smallest heel to be operated upon will engage them, insuring support. Pivoted to the plate 80 is a link 86, also articulated to a lever 88 fulcrumed upon the frame and having at its opposite extremity a roll 90. This roll is held by a spring 91, extending between the lever and the frame, against a cam-surface 92 formed upon the inner side of one of the gears 52. Upon the frame, adjacent to the link 86, is fulcrumed a lever 94 articulated to said link and joined by a link 96 to the opposite plate 82. Because 100 of the contour of the cam and the character of the connections just described, the plates are first held stationary in their inner position to receive a heel falling from the magazine. Then, after this heel has been clamped by the follower, pricked by the awls, and released, the plates are separated to free the heel, whereupon it falls through an opening in the frame, and may be received by a container placed beneath the opening.

At the time of discharge of the pricked heel, it is, of course, necessary that the remaining heels of the series in the magazine shall be held against downward movement until the supporting plates are again in a position to receive them. This I have shown as accomplished by a retaining member furnished by a plunger 98 arranged for horizontal movement in a bore located in one of the magazine-supporting plates 58. This member is reciprocated synchronously, or in predetermined time-relation, with the plates 80, 82, and consequently with the pricking mechanism, which is operated from the same driving mechanism. To accomplish this, the plate 82 is shown as having threaded horizontally through a boss upon its upper face a screw 100 contacting with a lever 102 fulcrumed upon the corresponding plate 58, and having at its upper end a fork embracing a pin 104 projecting from the retaining member. A spring 106 joins the lower end of the lever to the plate, exerting a force which tends to carry the plunger 98 against the heel above that supported upon the plates 80, 82. When these plates are in the heel-supporting position, as is illustrated in Fig. 1 of the drawings, the screw 100 contacts with the lever 102, and holds the member 98 clear of the path of the heels. The entire stack is consequently supported by the plates. After the pricking operation, as the plates separate and approach the breast-corners of the heel, the retreat of the screw 100 with the plate 82 permits the spring 106 to force the member 98 against the second heel, retaining this and the remainder of the stack in the magazine. Consequently, when the heel which has been operated upon is freed by the plates, it falls without affecting the contents of the magazine. When the plates 80, 82, in their reverse or inward movement, have attained points at which their edges are beneath the heels in the magazine, the screw again strikes the lever, which withdraws the retaining member, and the entire stack falls until the lowest heel rests upon the plates for the operation upon it. Since the retaining member 98 and all its actuating elements are carried by the plate 58 supporting the wall-section 54, through which said retaining member acts, adjustment of the wall-section by means of the screw 62 will not disturb the correct relation of the engaging end of the member to the heels in the magazine. Moreover, since the screw 100 and lever 102 are not directly connected, but are capable of moving into and out of contact with each other, this portion of the actuating chain does not interfere with the adjustment of the magazine.

Although the column of heels in the magazine exerts considerable pressure tending to prevent upward displacement of the heel fed from the magazine upon the supporting

plates and to which clamping pressure has been applied, this may not be sufficient, especially with wedge-heels. This is due to the fact that, for these, the contact-surface between the follower and the heel-seat-end 70 may be inclined at a substantial angle, diverging upwardly from the vertical. Consequently, the follower exerts a proportionate thrust upon the heel tending to displace it from the pricking position. To prevent this, when the follower acts, there is held in normally fixed relation upon the front face of the templet a heel-positioning member or gage-plate 108. Its lower edge is curved or inclined at 110, so that it may engage the rear of the heel upon the supporting plates 80 adjacent to the tread-surface at separated points. This gage-plate, at its vertical edges, is guided upon the templet by ways 112, and is adjustably maintained in a predetermined 80 vertical relation to the templet-openings by a collar 114 threaded upon the screw 18 and entering, at 116, a depression in the upper portion of the gage-plate. Rotation of the collar upon the screw will raise or lower the 90 gage-plate independently of any movement which may be imparted to the templet by turning the spindle 20. Consequently, the plate may be so adjusted that, for any size of heel to be operated upon and any pricking design which may be employed, the inclined edge 110 may be caused to just overhang the rear of the heel adjacent to the tread-surface when said heel is resting upon the plates 80 and 82. The heel-engaging 100 edge 110 is not only so inclined that its upwardly converging portions contact with opposite sides of the rear of the heel, but is also tapered or inclined from the templet outwardly, it diverging slightly from the 105 face of said templet. This renders it more certain that the heels will enter beneath the gage-plate when follower-pressure is applied, and will thereby be seated in firm engagement with the templet and with both the 110 supporting plates and the edge of the gage. The last-mentioned effect, by virtue of the upward convergence of the contact-edge, centers the engaged heel transversely of the templet. 115

In using the apparatus, the operator, as usual, provides a templet having the chosen design, an awl-block with its awls correspondingly arranged and a follower suitable for co-operation with the form of heel to be operated upon, and adjusts the dimensions of the magazine to correspond to said heels. In the latter instance, the wall-sections 54 are located by means of the screws 62 to correspond to the width of the heels; the nuts 72 cause the wall-sections 56 to be shifted in proportion to the height of the heels; while contact of the follower with the heel-seat-ends is arranged for by raising or lowering the sections 56 under the clamping control of 120 125 130

the nuts 76. Adjustment of the screw 100 determines the time of release from the templet and pressure member.

plunger 98 of the heels in the magazine above that being operated upon. This magazine may be filled by the operator with a series of heels, the lowest resting upon the plates 80, 82 breast down, and the succeeding heels upon such lowest heel and upon one another. When the machine is started, 10 the follower 40 clamps the heel resting upon the supporting plates against the templet, the springs 46 yielding to compensate for any excess of movement of the follower over that necessary to provide the proper clamping pressure. Then the awls pierce the clamped heel, are drawn back, and the pressure of the follower is removed. Upon this, 15 the cam 92 causes the separation of the supporting plates 80 and 82 and the discharge 20 of the pricked heel from the machine. Before this heel falls, release of the lever 102 from the screw 100 upon the plate 82 has left the spring 106 free to apply retaining pressure to the second heel in the series in the 25 magazine by the member 98. This holds the contents of the magazine during the discharge of the heel, and, when the cam has again allowed the supporting plates to return into the path of the heels, the screw 100 30 retracts the member 98, and the column descends, bringing the terminal heel into pricking position upon the plates. The supply of heels in the magazine may be replenished when exhausted, or when convenient for the 35 operator.

Having described my invention, what I claim as new and desire to secure by Letters Patent of the United States is:

1. In a machine for operating upon heels, 40 heel-pricking mechanism, and a heel-container arranged to deliver heels directly to the pricking mechanism with the contained stack supported by a heel in pricking position.

2. In a machine for operating upon heels, 45 heel-pricking mechanism, and a heel-container arranged to deliver by gravity directly to the pricking mechanism.

3. In a machine for operating upon heels, a horizontally movable operating member, 50 and a container organized to hold a vertical series of heels and arranged to deliver by gravity to the operating member.

4. In a machine for operating upon heels, 55 heel-pricking mechanism, a heel-container extending upwardly from and arranged to deliver to the pricking mechanism, and means arranged to permit the relation of the container to the pricking mechanism to be varied.

60 5. The combination with a templet, of awls co-operating therewith, and a heel-magazine arranged to deliver to the templet.

65 6. The combination with a templet, of awls co-operating therewith, a pressure member spaced from the templet, and a heel-

magazine rising above the space between the templet and pressure member. 7. The combination with a templet, provided with openings, of awls operating in the magazine, a heel-magazine situated above the templet, and means arranged to vary the relation of the magazine-walls to the templet-openings. 70

8. In a machine for operating upon heels, heel-pricking mechanism, a heel-container, means arranged to deliver heels from the container directly to the pricking mechanism. 75 a retaining member controlling the delivery of heels from the container to the pricking mechanism, a support for the heels during the pricking operation and to which the container delivers, and means for moving the support to discharge the pricked heels. 80

9. In a machine for operating upon heels, 85 pricking mechanism, a movable support co-operating therewith, a container for a series of heels delivering to the pricking mechanism, movable means for retaining heels in the container, and means for operating the pricking mechanism and moving the supporting and retaining means in synchronism. 90

10. In a machine for operating upon heels, 95 pricking mechanism, a movable support co-operating therewith, a container for a series of heels delivering to the pricking mechanism, movable means for retaining heels in the container, means for operating the pricking mechanism and moving the supporting and retaining means in synchronism, and means arranged to vary the time-relation between the operation of the supporting and retaining means. 100

11. The combination with a templet, of awls co-operating therewith, a heel-support movable below the templet, a magazine for a series of heels situated above the templet, a movable heel-retaining member co-operating with the magazine, and means for successively moving the member into retaining engagement with a heel and the support to release a heel. 105 110

12. The combination with pricking mechanism, of a magazine delivering thereto, movable supporting members co-operating with the pricking mechanism and magazine, and means for moving said members simultaneously in opposite directions. 115

13. The combination with pricking mechanism, of a magazine delivering thereto, a pair of members movable beneath the magazine, and means for oppositely reciprocating the members. 120

14. The combination with pricking mechanism, of a magazine delivering thereto, a movable supporting member co-operating with the pricking mechanism and magazine, a retaining member associated with the magazine, and means operated by the supporting member for actuating the retaining member. 125

15. The combination with pricking mecha- 130

nism, of a magazine delivering thereto, a movable supporting member co-operating with the pricking mechanism and magazine, a retaining member associated with the magazine, means operated by the supporting member for actuating the retaining member, and means arranged to vary the time of actuation of the retaining member.

16. The combination with pricking mechanism, of a magazine delivering thereto, a slide movable beneath the magazine, a movable retaining member associated with the magazine, and contact means carried by the slide for co-operation with the retaining member.

17. The combination with pricking mechanism, of a magazine delivering thereto, a slide movable beneath the magazine, a movable retaining member associated with the magazine, and means for normally holding the member in retaining position, the slide having a projection for moving said member out of the retaining position.

18. The combination with pricking mechanism, of a magazine delivering thereto, a slide movable beneath the magazine, a movable retaining member associated with the magazine, means for normally holding the member in retaining position, and a screw carried by the slide for contact with said moving means.

19. In a machine for operating upon heels, operating mechanism, a heel-container delivering to the operating mechanism and including an adjustable wall-section, and means arranged to move with the wall-section and controlling delivery from the container.

20. In a machine for operating upon heels, operating mechanism, a heel-container delivering to the operating mechanism and including an adjustable wall-section, and a reciprocatory heel-retaining member guided on and adjustable with said section.

21. In a machine for operating upon heels, operating mechanism, a heel-container delivering to the operating mechanism and including an adjustable wall-section, a heel-retaining member arranged to reciprocate upon said section and being adjustable therewith, and operating members for the retaining member, one of said operating members being movable into and out of contact with another.

22. In a machine for operating upon heels, operating mechanism, a heel-container delivering to the operating mechanism and including an adjustable wall-section, means movable upon the wall-section for controlling delivery from the container, a movable support for the delivered heels below the container, and means movable with the support for operating the controlling means.

23. In a machine for operating upon heels, operating mechanism, a container delivering thereto and having a plurality of walls, and means organized to support one of said walls

upon another and to permit the supported wall to be adjusted in directions at different angles to the operating mechanism.

24. In a machine for operating upon heels, operating mechanism, a container delivering thereto and having a plurality of walls, and means organized to support one of said walls upon another and to permit the supported wall to be varied in position toward and from the operating mechanism and toward and from the companion wall.

25. In a machine for operating upon heels, operating mechanism, a container delivering thereto and having four wall-sections, means arranged to permit two of the sections to be moved toward and from each other, and means for variably supporting the other two sections upon those just mentioned.

26. In a machine for operating upon heels, operating mechanism, a container delivering thereto and having four wall-sections, means arranged to permit two of the sections to be moved toward and from each other, and means for variably supporting the other two sections upon those just mentioned, such variable sections being arranged for movement in a plurality of directions.

27. In a machine for operating upon heels, operating mechanism, a container delivering thereto and having four wall-sections, means arranged to permit two of the sections to be moved toward and from each other, and means for variably supporting the other two sections upon those just mentioned, such variable sections being arranged for movement toward and from the companion sections and toward and from the operating mechanism.

28. In a machine for operating upon heels, a templet, reciprocatory awls co-operating with the templet, and a magazine delivering to the templet and having opposite wall-sections variable in position laterally of the path of the awls and other sections variable in position in the direction of movement of the awls.

29. In a machine for operating upon heels, a templet, reciprocatory awls co-operating with the templet, and a magazine delivering to the templet and having opposite wall-sections variable in position laterally of the path of the awls and other sections variable in position in the direction of movement of the awls and toward and from said awls.

30. In a machine for operating upon heels, a vertical templet, horizontally reciprocatory awls co-operating with the templet, a magazine rising above the templet and having a pair of wall-sections at each side of the templet, and means arranged to vary horizontally the position of each of the sections.

31. In a machine for operating upon heels, a vertical templet, horizontally reciprocatory awls co-operating with the templet, a magazine rising above the templet and having a pair of wall-sections at each side of the

templet, means arranged to vary horizontally the position of each of the pairs of sections, and means arranged to vary vertically the position of one of the sections of each 5 pair.

32. In a machine for operating upon heels, operating mechanism, a magazine delivering to the operating mechanism and having a plurality of wall-sections, an adjusting device 10 vice carried by one section and arranged to support and variably position another section, and means arranged to variably position the last-named section upon the adjusting device.

33. In a machine for operating upon heels, a vertical templet, horizontally reciprocating awls co-operating with the templet, a magazine rising above the templet and having a pair of wall-sections at each side of the 20 templet, an adjusting device projecting from one of the wall-sections of each pair and arranged to vary the position of the companion wall-section in the direction of movement of the awls, and means arranged to 25 vary the vertical position of the last-named wall-sections.

34. In a machine for operating upon heels, a vertical templet, horizontally reciprocating awls co-operating with the templet, a 30 magazine rising above the templet and having a pair of wall-sections at each side of the templet, an adjusting device projecting from one of the wall-sections of each pair and arranged to vary the position of the companion 35 wall-section in the direction of movement of the awls, means arranged to vary the vertical position of the last-named wall-sections, and means arranged to vary the position of each 40 pair of wall-sections horizontally transversely of the path of the awls.

35. In a machine for operating upon heels, operating mechanism, and a heel-magazine delivering thereto and comprising a wall-section, a projection from said section, a 45 member movable upon the projection, and a wall-section movable upon the member.

36. In a machine for operating upon heels, operating mechanism, and a heel-magazine delivering thereto and comprising a wall-section, a projection from said section, a member mounted upon the projection, means 50 arranged to vary the position of the member upon the projection, and a wall-section mounted upon the member.

37. In a machine for operating upon heels, operating mechanism, a heel-magazine delivering thereto and comprising a wall-section, a projection from said section, a member mounted upon the projection, means 55 arranged to vary the position of the member upon the projection, a wall-section mounted upon the member, and means arranged to vary the position of said section.

38. In a machine for operating upon heels, 60 operating mechanism, a heel-magazine deliv-

ering thereto and comprising a wall-section, a stud projecting from the section, a sleeve movable upon the stud and provided with a projection, a wall-section having an opening receiving the projection, and means arranged to determine the position of the sleeve upon the stud and of the wall-section upon the projection.

39. In a machine for operating upon heels, operating mechanism, a heel-magazine delivering thereto and comprising a wall-section, a threaded stud projecting from the section, a sleeve movable upon the stud and having a threaded projection, a nut upon the stud limiting the movement of the sleeve, a spring interposed between the wall-section and sleeve, a wall-section having a slot to receive the projection, and a nut upon the projection arranged to fix the position of the last-mentioned wall-section.

40. In a heel-pricking machine, pricking mechanism including a templet, and a heel-positioning member cooperating with the templet and fixed against movement in the 90 operation of the machine.

41. In a heel-pricking machine, pricking mechanism including a templet, and a heel-positioning member co-operating with the templet and fixed against movement in the operation of the machine, said positioning 95 member being constructed and arranged to resist in a plurality of directions movement of a heel under the influence of the forces applied for pricking.

42. In a heel-pricking machine, pricking mechanism including a templet, and a heel-positioning member co-operating with the templet and fixed against movement in the operation of the machine, said positioning member being constructed and arranged to 100 exert a force upon a heel transversely of the direction of application of the pricking force.

43. In a heel-pricking machine, pricking mechanism including a templet, a heel-positioning member co-operating with the templet and fixed against movement in the operation of the machine, and means arranged to adjust the normal relation between the templet and positioning member.

44. In a heel-pricking machine, a heel-magazine, pricking mechanism situated below the magazine and to which it delivers, said pricking mechanism including a templet, and a heel-gage supported upon the templet.

45. In a heel-pricking machine, a heel-magazine, pricking mechanism situated below the magazine and to which it delivers, said pricking mechanism including a templet, and a gage supported upon the templet and having oppositely inclined surfaces arranged 115 to engage a heel.

46. In a heel-pricking machine, a heel-magazine, pricking mechanism situated below the magazine and to which it delivers, said pricking mechanism including a templet, and 120

a gage supported upon the templet and having oppositely inclined surfaces arranged to engage a heel, said engaging surfaces diverging outwardly from the templet.

47. In a heel-pricking machine, a heel-magazine, pricking mechanism situated below the magazine and to which it delivers, said pricking mechanism including a templet provided with awl-openings, a heel-gage supported upon the templet, and means connecting the templet and gage and arranged to vary the relation of the gage to the templet-openings.

48. In a heel-pricking machine, a templet, a gage-plate movable thereon, said templet and gage-plate being provided with co-operating ways guiding the gage-plate.

49. In a heel-pricking machine, a templet, a heel-positioning member co-operating with the templet, and a member arranged to vary the position of the templet, said member having means arranged to vary the position of the positioning member independently of the position of the templet.

50. In a heel-pricking machine, a templet, a gage-plate movable thereon, a screw arranged to position the templet, and a threaded member carried by the screw and co-operating with the plate to effect its movement.

51. In a heel-pricking machine, a templet, a member arranged to press a heel against the templet, and means for actuating the member and including yieldable connections to said member.

52. In a heel-pricking machine, a templet, a movable follower spaced from the templet, a magazine arranged to deliver heels between the templet and follower, means for actuating the follower, and yieldable connections between the follower and actuating means.

53. In a heel-pricking machine, a templet, a heel-gage co-operating with the templet, a magazine arranged to deliver heels into co-operation with the templet and gage, and a follower organized to press the delivered heels against the templet and gage.

54. In a heel-pricking machine, a templet, a heel-gage co-operating with the templet, a magazine arranged to deliver heels into co-operation with the templet and gage, a follower organized to press the delivered heels against the templet and gage, and actuating means for the follower and including yieldable connections.

55. In a heel-pricking machine, a templet, a slide movable toward and from the templet, a follower movable upon the slide and arranged for co-operation with the templet, springs interposed between the follower and slide, and means for reciprocating the slide.

In testimony whereof I have signed my name to this specification.

JOSEPH H. POPE.
